United States Patent Office

Des. 198,140
Patented May 5, 1964

198,140

INSTRUMENT HOUSING

William Carpenter and Byron Stenholm, Muskegon, Mich., assignors to Carpenter Corporation, Muskegon, Mich., a corporation of Michigan

Filed Dec. 10, 1963, Ser. No. 77,740

Term of patent 14 years

(Cl. D52—6)

FIG. 1.

FIG. 2.

FIG. 3.

FIG. 4.

FIG. 1 is a perspective front view of the instrument housing of this invention;

FIG. 2 is a side elevational view of the instrument housing shown in FIG. 1;

FIG. 3 is a plan view of the instrument housing shown in FIG. 1;

FIG. 4 is a bottom view of the instrument housing of this invention.

The side of the instrument housing opposite that illustrated is identical to the side illustrated. The rear of the housing is substantially plain in appearance.

We claim:

The ornamental design for an instrument housing, substantially as shown and described.
